Patented May 23, 1916.

Fig. 2.

Inventor:
EDMOND G. GEORGE,
By John H. Brumaga,
His Attorney.

UNITED STATES PATENT OFFICE.

EDMUND G. GEORGE, OF SPRINGFIELD, ILLINOIS.

LAMP-SHADE.

1,184,676.

Specification of Letters Patent. Patented May 23, 1916.

Application filed July 12, 1915. Serial No. 39,509.

To all whom it may concern:

Be it known that I, EDMUND G. GEORGE, a citizen of the United States, and residing at Springfield, in the county of Sangamon and State of Illinois, have invented a certain new and useful Improvement in Lamp-Shades, of which the following is a specification.

This invention relates to lamp shades, designed especially for use with incandescent lamps and of the type having transparent or translucent sections or panels for softening the light and producing ornamental effects.

Prior devices of this class have contemplated the use of glass panels or sections, these being objectionable, however, not only because of the cost incident to their use, but also because of the fact that because of this cost they become a permanent fixture unadaptable for ready changing in instances where different colored light effects are desirable, as in the instance of certain social functions. The use of glass panels is also objectionable for the reason that they necessitate the use of heavy and expensive frames for holding them, and because the extreme weight of the resultant shade necessitates the provision of special clamping devices for properly attaching them in position on the lamp.

This invention has for its objects to overcome the objections noted, by the production of a simple, inexpensive shade of minimum weight, which may be readily applied in position for use, and this without the provision of expensive attaching means; one in which the transparent or translucent panels are of an exceedingly inexpensive nature, and are, therefore, susceptible of being changed at slight expense for changing the color of the shade to produce desired light effects, and one wherein this changing of the panels may be readily and effectually accomplished.

With these and other objects in view, the invention comprises the novel features of construction and combination of parts more fully hereinafter described.

In the accompanying drawings; Figure 1 is a side elevation of an electric lamp fixture equipped with a shade embodying the invention; Fig. 2 is a top plan view, partly in section, the section being taken on the line 2-2, Fig. 1; Fig. 3 is a vertical section taken on the line 3-3, Fig. 1, of the shade, showing the same applied to the lamp fixture; and,

Fig. 4 is a detail perspective view of the clamping means for holding the shade in place on the fixture.

Referring to the drawing, 1 designates an electric lamp socket provided, adjacent its lower end, with a peripheral flange 2, and fitted with an incandescent lamp globe 3, these parts, which are foreign to the invention, being of the usual construction and material.

The lamp shade forming the subject matter of the invention consists of a cap 4, a skeleton body frame 5, and transparent or translucent sections or panels 6, the latter being composed of heavy oiled paper, and removably held in the frame 5 by means of downturned engaging portions or fingers 7 at the upper end of the frame, and upturned flanges 8 at the lower edge of the frame.

The cap portion 4, which is formed from a single piece or blank of thin sheet metal, and in a single operation, is provided with a central fixture receiving opening 9, a downturned marginal flange 10, and a plurality of apertures 11 arranged at diametrically opposite points, and at a suitable spaced distance inward from the margin of the cap, there being provided at suitable points 35 around the opening 9 and in the operation of forming the cap, radial tongues or fingers 12, having their ends bent upwardly and backwardly upon themselves, thus to form spring clamping fingers for engagement 90 with the lamp socket 1 above the rib 2, as seen more clearly in Fig. 3.

The body 5, which is formed from a single blank of thin sheet metal having portions cut out to form side openings 13 through 17, in which the paper 6 is exposed, these openings being separated by suitable webs 14, 15, 16 and 17, of which the webs 16 form the vertically disposed corners of the frame when the blank is folded in completed rectangular form, as indicated by dotted lines in Fig. 2, it being noted that when thus folded the meeting ends of the blank are united at one corner of the frame by means of tongues 18 formed on one of the webs 16, and engaging through slotted apertures 19 formed in the adjacent web, while formed on the upper edge of the blank are tongues 20 corresponding in number to, and properly positioned for engagement through, the perforations 11, for attaching the body frame to the cap 4. In the stamping operation incident to

formation of the body blank, the latter is incised at appropriate intervals along its upper and lower edges, to provide for formation of the fingers 7 and flanges 8, the metal 5 which is to form these parts being folded inward and outward respectively upon the webs 15 and 16 for engagement with the adjacent edges of the sheets 6, as seen more clearly in Fig. 3, it being noted that coincident with the formation of the fingers 7 there are provided at the upper edge of the body suitable ventilating openings 21.

In practice, in order to apply the shade to the lamp fixture, the globe 3 is removed 15 and the lower end of the lamp socket 1 positioned in the opening 9, whereupon, by upward pressure on the shade, the fingers 12 will spring over the rib 2 and into clamping engagement with the socket at a point above 20 said rib, it being noted, in this connection, that, owing to the extreme lightness of the shade as a whole, the fingers 12 will adequately serve for properly securing the shade in position on the lamp. When the 25 shade is in position, the transparent or translucent panels 6 will appropriately soften or color the light radiated from the lamp, and when it is desired to change the panels to accord with a particular color scheme, or to vary the monotony incident to the continuous use of a shade of a certain color, the paper sheets or panels may be 30 readily removed and replaced by others of a different color, the range of such changes 35 being practically indeterminate and susceptible of being made with very slight expense. In fact, it is the purpose in marketing the device, to provide a number of sets of panels 6 of different colors, to be interchanged at 40 will. It is evident that the several component parts of the shade are of extreme simplicity in construction, and are so formed that they may be readily set up in completed form for use, and further, that they are all 45 produced from light weight material,

whereby the device as a whole may be inexpensively produced, and may be applied to the lamp and properly supported thereon by means of the simplified form of clamps herein shown.

It is obvious that various changes may be made in the details of construction without departing from the spirit of this invention. It is, therefore, to be understood that this invention is not to be limited to the specific construction shown and described. 55

Having thus described the invention, what is claimed is:

1. A lamp shade comprising a body frame and a cap, each of said parts being formed 60 from a single sheet of material, said cap having an opening and a plurality of radial spring fingers projecting into said opening, and means for attaching the cap to the body.

2. A lamp shade comprising a body frame 65 and a cap, each formed from a single sheet of material and having integral interengaging portions for attaching the cap to the body, said cap having an opening and a plurality of radial spring fingers projecting 70 into said opening.

3. A lamp shade comprising a body frame and a cap, said body frame being formed from a single sheet of material and having enlarged panel openings, paper panels arranged in the body frame to cover said openings, and means on said body frame for 75 holding the panels in place.

4. A lamp shade comprising a body frame and a cap, said body frame being formed 80 from a single sheet of material and having enlarged panel openings, inturned engaging lips formed integral with said body frame at opposed sides thereof, and paper panels arranged in the body frame in engagement 85 with said lips and to cover said openings.

In testimony whereof I affix my signature this 28th day of May, 1915.

EDMUND G. GEORGE.
